US0D1033266S

(12) **United States Design Patent** (10) **Patent No.:** **US D1,033,266 S**
(45) **Date of Patent:** **** Jul. 2, 2024**

(54) **CRIMPING PLIERS**

(71) Applicant: **Zhejiang Fulisi Tools Co., Ltd.**,
Wenzhou (CN)

(72) Inventor: **Ji Chen**, Yueqing (CN)

(73) Assignee: **Zhejiang Fulisi Tools Co., Ltd.**,
Wenzhou (CN)

(**) Term: **15 Years**

(21) Appl. No.: **29/908,325**

(22) Filed: **Jan. 11, 2024**

(51) LOC (14) Cl. **08-05**

(52) U.S. Cl. **D8/52**

(58) **Field of Classification Search**

USPC D8/51-60

(57) **CLAIM**

The ornamental design for a crimping pliers, as shown and described.

DESCRIPTION

FIG. 1 is a front, right, and top perspective view of a crimping pliers, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the crimping pliers that form no part of the claimed design.

1 Claim, 8 Drawing Sheets

FIG. 1

FIG. 2

FIG. 3
